REFRIGERATOR VEHICLE

David C. Arthurs and Jesse A. Guyer, Mount Vernon, Ill., assignors to Mt. Vernon Car Mfg. Co., Mount Vernon, Ill., a corporation of Illinois

Application November 21, 1936, Serial No. 111,978

1 Claim. (Cl. 62—91.5)

This invention relates to refrigerator vehicles, and with regard to certain more specific features, to cars and trucks of a type adapted to be used on railways, highways, and the like.

Among the several objects of the invention may be noted the provision of means for converting the water-ice compartments now used in refrigerator vehicles into an effective dry-ice compartment (carbon-dioxide-ice); the provision of apparatus of the class described which shall make maximum use of the facilities now available in connection with water-ice cooling compartments but which will avoid their disadvantages; the provision of apparatus of the class described which is automatic in maintaining desirable temperatures in the car, without effecting excessively cooled areas therein; and the provision of improved apparatus of the class described in cars not previously provided with any means of refrigeration. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claim.

In the accompanying drawings, in which are illustrated several of various possible embodiments of the invention,

Fig. 1 is a longitudinal section of an end of a railway refrigerator car (for example), showing the invention;

Fig. 2 is a vertical section taken on line 2—2 of Fig. 1;

Fig. 3 is an enlarged detail showing certain damper operating means;

Fig. 4 is a view similar to Fig. 1 showing a modification; and,

Fig. 5 is a vertical section taken on line 5—5 of Fig. 4.

Similar reference characters indicate corresponding parts throughout the several views of the drawings.

Many railway refrigerator cars and highway motor cars or trucks are now equipped with water-ice compartments for refrigeration enroute. It has been proposed to use, instead of the water-ice refrigerant, the now available and so-called dry-ice, or frozen carbon-dioxide (CO₂).

The most serious objection to using dry-ice as a refrigerant, without some means of controlling the temperature, is its low temperature (minus 109° F.), which is below the freezing

point of most all materials transported in such equipment. Although many systems have been proposed to control the rate of refrigeration and maintain the desired temperature in the body of a car or truck, most of the proposed systems are too expensive to install, require frequent repairs, and require moving parts such as fans and pumps.

The use of the ordinary secondary refrigerating materials is objectionable because of their original expense and possible injurious effect upon the material being transported. Such materials increase the weight of the non-pay load, and when they leak out of the system damage the pay load. Materials such as alcohol are highly inflammable and are a fire hazard.

The system described herein is designed to overcome the above-mentioned difficulties of the previous systems, and can be installed in the present refrigerated cars or trucks with a minimum of expense both for installation, operation, and up-keep. One of the most important features of this system is that it can be installed in refrigerator cars originally equipped to use water-ice. Consequently, the car can be refrigerated with either dry-ice or water-ice as conditions require. It eliminates the deleterious secondary refrigerants and all moving parts such as fans or pumps, requiring power for operation. The initial cost of installation is low, and there is practically no up-keep cost. The invention also prevents the relatively cold dry-ice refrigerant from locally over-cooling the region of the car adjacent the dry-ice compartment.

Referring now more particularly to Fig. 1, there is illustrated by way of example the end of a railroad refrigerator car having an insulated top 1, an insulated bottom 3, insulated side walls 5, and insulated end walls 7. Heretofore cars of this type have been provided at their ends with water-ice compartments or bunkers which have been separated from the remainder of the car merely by a suitable separating wall. Inasmuch as this compartment was filled with water-ice through an opening such as shown at 11, and said water-ice could never attain a temperature while melting less than 32° F., there was never experienced any trouble of local freezing adjacent to said separating wall. However, when compartments such as 9 are loaded with dry-ice, the temperatures adjacent the separating wall are so low as to locally freeze products adjacent the wall without efficiently cooling the remaining products in the car.

The present invention comprises the separa-

ing wall 13 between refrigerant compartment 9 and the load compartment 5. The compartment 9 is left as an air space. Preferably spaced from the wall 13 is a dry-ice container 15. The dry-ice container 15 is also preferably positioned opposite the now available opening 11 so that filling may be accomplished through said opening 11.

Adjacent the wall 13, on the side of the compartment 9, is a duct 17 between which and the refrigerant compartment 9 is a metal, heat-conducting wall 19.

Into the duct 17 lead return upper ducts 20 and 21 located at the sides of the car and near the ceiling. These ducts are provided with return openings 23 and control valves or dampers 25. By means of parallel linkages 27 the valves 25 are coupled with a valve 28 at the lower end of the duct 17. The linkage, as shown in the drawings, is such that the valves 25 and 28 operate in unison to open and close.

Leading from the lower end of the duct 17 are two delivery ducts 31 in opposite corners of the bottom of the car, and these have outlets 33, through which cold air emanates into the load compartment 5.

The valves or dampers 25 and 28 are provided with operating means by coupling a stem 37 to the lever 35 of one of the valves 25 (Fig. 3). The stem 37 is attached to one closed end of a flexible, extensible, metallic bellows 39. A return spring 41 normally presses the end 37 in the direction to compress the bellows 39. The interior of the bellows 39 communicates at its other end, by means of a flexible tube 43, with the inside of a fluid chamber 45. The chamber 45 has therein a volatile fluid such as ether or the like, which has a useful vapor pressure at the temperatures over which refrigerating control is to be effected. The vessel 45 is placed at a suitable point within the car for responding to temperature changes.

The vessel 15 may be referred to as the dry-ice chest and it is gas-tight when closed, with the exception of a lower small opening 47 through which the gas formed by the sublimation of the dry-ice sinks to the outside atmosphere. It is to be understood that the chest 15 is made of metal and is not insulated so that it quickly cools the air in the chamber 9. The air in the chamber 9 has a tendency to circulate as indicated. It circulates down on the side of the ice chest 15 and up adjacent to the wall 19.

It will be seen that by venting the ice chest 15 directly to the outside atmosphere, that the refrigerant compartment 9 can be and is maintained entirely closed without any inside pressure. Furthermore air circulation in the refrigerator compartment 9 will be unhampered therein by any outside connection.

Operation is as follows: The car is loaded with a pay load in the compartment 4, and vessel 13 is filled with frozen carbon-dioxide. When the load is placed in the car, its temperature being high, heat is transferred to the volatile fluid in the member 45, which expands and elongates the bellows 39 against the action of spring 41. This causes the lever 35 to be thrown to a position wherein the valves 25 and 28 are thrown toward open position. This allows circulation of air down through the duct 17 (by reason of increase in density as the air cools), out from the ducts 31, up through the load, and returning to the duct 17 via the ducts 20 and 21. As the load cools the fluid in the chamber 45 contracts, thus contracting the bellows 39, thus tending to shut off the valves 25 and

29. It will be seen that there is a counter-flow between the rising air on the one side of the metal wall 19 and the descending air on the other side in duct 17, this being conducive to a high efficiency of heat transfer. Whenever the load tends to warm up, the cycle tends to repeat itself.

An advantage of having the ice chest 15 located at a point spaced from the wall 19 is that the air within the compartment 9 forms an intermediate, safe, inexpensive secondary circulating medium 10 for absorbing heat generally over the whole wall 19, rather than permitting the exceedingly cold carbon-dioxide to abstract heat from this wall at a high rate over a local region which would tend to excessively cool the air at one point, and to increase the condensation and dehumidification of the contents of the pay load. Such humidification is undesirable, and it is the function of the circulating air in the compartment 9 to reduce the temperature head across the wall 19, and thus hold the air in the duct 17 at as high a temperature as possible consistent with the desired cooling effect. This reduces the condensation and maintains the pay load at a higher humidification. Inasmuch as the entire condensation cannot be eliminated, a suitable drain 53 is provided in the bottom of the duct 17.

The reason for the valve 28 being at the junction between the ducts 20 and 21 with the duct 17 on the one hand, and the valve 28 at the base of the duct on the other hand, is to effectively block off any local circulation up and down through the duct 17 from its bottom when the thermostatic apparatus calls for no more cooling effect.

It is to be understood that the responsive member 45 may be positioned at any suitable point within the car, and it may be movable. Also, several controls may be used and connected to independent duct systems, if desired. It is also to be understood that the control characteristics of the thermostatic system may be varied by adjustment of a suitable control screw 55 which varies the reaction characteristics of spring 41. Thus the temperature of the car may be adapted to the load which it carries. In this connection, one of the advantages of the use of dry-ice is that meat products and the like may actually be frozen in the car; whereas this could not be done with plain water-ice. At the same time, the freezing temperatures need not be endured by loads which are not adapted to them.

In Figs. 4 and 5 is shown another form of the invention in which like numerals designate like parts. Many refrigerator cars are provided with battens forming a false, reticulated bottom so that the products in the car do not rest directly upon the main bottom of the car. This is to obtain circulation thereunder. Advantage is taken of this construction by applying over battens 61 a false bottom 63 having openings 65 therein, thus providing the equivalent of the lower side ducts 31 used in the form of the invention shown in Figs. 1 and 2.

The spaces between the battens 61 and under the bottom are in direct communication with the lower end of the duct 17. This form of the invention also results in excellent distribution of the cool air beneath the load.

Another modification shown in Figs. 4 and 5 is the substitution for two of the upper valves 25, 70 of a single valve 26 which reaches across the entire upper end of the passage 17. In this case there is substituted for the passages 20 and 21 of Figs. 1 and 2 a single flat passage 28 extending across the entire roof of the car having 75

openings 30 through which openings 30 takes place circulation from the load. The stem 31 from the member 39 passes loosely through an opening in the bottom of passage 28. This is proper because such an opening performs a circulating function similar to the opening 30. Duplicate control links 27 are indicated as connecting the single valve 26 and valve 29 in Figs. 4 and 5, but it will be understood that in this case one of these (for example, the left-hand link 27 in Fig. 5) may be eliminated. However, duplicate links serve to facilitate steady action.

It will be apparent to anyone skilled in this art that the single valve 26 in Figs. 4 and 5 serves a function similar to the valves 25 in Figs. 1 and 2. The valve 26 in Figs. 4 and 5 primarily increases the cross section of the air circuit at the region where said circuit is controlled.

A feature of the invention is the provision of the valve means 25 or 26 at the upper end of the duct 17 and of the valve means 29 at the lower end thereof. This valve means, when shut, results in blocking off substantially all of the cooling area of the wall 19 from communicating with the load compartment 4. It is this cutting off of communication which prevents local circulation through any communicating means, whereby uncontrolled and undesired cooling would proceed. The small area of the wall 19 below the valve 29 is of little consequence in obtaining the result here referred to. If desirable, even this small area may be included between the valves 25 and 29 by placing the valve 29 directly at the outlet ducts 22. The reason they are not thus shown is that it is more convenient to have the valve 29 in the location shown in the drawings.

Further advantages of the invention are that, inasmuch as control of the otherwise excessively low temperature produced by the dry-ice is provided for, use can be made of the desirable dry-ice form of refrigeration which has a theoretical heat absorption value as compared with water-ice of roughly two to one on a weight basis. Practically the ratio is even higher because of the increase in efficiency of the method herein disclosed of handling the dry-ice.

Another feature of the invention lies in the fact that advantage is taken of the maximum fluid-circulating head obtainable by making the duct 17 run from the top of the car (and top of the refrigerating compartment) to the bottom of the car (and bottom of the refrigerating com-

partment). By this means the rate of gravity-induced circulation of air is made a maximum. This means that the cold fluid in the refrigerating compartment and the warmer fluid in the duct 17 are not only in contact for a maximum period but also have the added effect of prolonging the period of heat exchange and thus improving the convection currents, both within the refrigerating compartment and throughout the ducts connected with the load compartment.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

We claim:

A refrigerator vehicle comprising a load compartment, a refrigerating compartment separated from the load compartment and containing secondary air, a duct extending from the top of the load compartment and entering into the top of the refrigerating compartment, said duct passing down through the refrigerating compartment and leaving at the bottom to enter said load compartment near its bottom whereby primary air circulation may be induced by gravity in the duct in a direction such as to flow down within the portion of the duct that is in the refrigerating compartment and up through the load compartment, at least one wall of said duct comprising a heat transmitting wall in the refrigerating compartment, a closed and substantially gas-tight dry-ice chest in said refrigerating compartment and spaced from said heat transmitting wall so as to compel a gravity circulation of secondary cooling air in the refrigerating compartment and between the dry-ice chest and said heat transmitting wall, the flow of said cooling air adjacent said wall being upward and counter to the flow of said primary circulation within the duct, the gravity circulation of secondary air being independent of any circulation of primary air, or of material in the chest and means for discharging gas from the dry-ice chest to the atmosphere.
